UNITED STATES PATENT OFFICE.

BERT NELSON, OF SPOKANE, WASHINGTON.

CLOTHES-WASHER.

1,275,077.

Specification of Letters Patent.

Patented Aug. 6, 1918.

Application filed September 8, 1917. Serial No. 190,359.

To all whom it may concern:

Be it known that I, BERT NELSON, a citizen of the United States, residing at Spokane, in the county of Spokane and State of Washington, have invented a new and useful Clothes-Washer, of which the following is a specification.

The subject of this invention is a clothes washer wherein a rotary dasher operates to force clothing over an uneven surface, and the objects of the invention are first, to provide a dasher for a clothes washer provided with novel end perforations, second, to provide means for expressing water from clothing at intervals, third, to provide a novel irregular surface for the interior of a washer, fourth, to provide a novel and efficient washer.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

A practical embodiment of the invention is shown in the accompanying drawing, wherein:

Figure 1 is an elevation of a washer constructed in accordance with the invention.

Fig. 2 is a central vertical section.

Fig. 3 is a section on the line 3—3 of Fig. 2.

Fig. 4 is a plan view with the top removed.

Referring to the drawings by numerals of reference:

A suitable support is provided which consists of corner uprights or legs 1 which are, by preference, formed of angle iron. Diagonal braces 2 may extend from the tops of legs 1 to the bottoms of the adjoining legs 1 for the purpose of rendering the base or support more secure or solid.

Seated upon this support is a tank or receptacle 3 which may be of any suitable and convenient shape but is here shown as of rectangular cross section. The tank or receptacle 3 may be secured to the base or support by means of the tie members 4 which are also formed of angle iron and have their lower ends secured to the upper ends of the legs 1 while their upper ends meet in a point

at the center of the upper edge of a side of the tank 3. As will be seen, these tie pieces form an inverted V.

Within the tank or receptacle 3, and arranged at opposed sides thereof and resting on the bottom, are diamond shaped plates 5 which are arranged on an incline over the angles formed by the meeting of opposed sides with the base of the tank 3. These plates 5 are provided with a series of apertures 6, which are preferably arranged in pairs and extend along either side of the ridge of said plates. A front strip 7, also of diamond shape, may be arranged to extend vertically from the floor of the tank and connect to and support the lower edge of each plate 5. Each strip 7 may be provided with a central aperture 8 to permit proper circulation of the water.

It will be understood from the foregoing that the plates 5 and strips 7 form with the bottom and sides of the tank 3, a hollow space which is in communication with the tank through the ports 6 and 8 and that free circulation of the water through these compartments is had.

Similar diamond shaped plates 9 are secured at the other opposed sides of the tank at the top edges thereof and overlie the angle formed by the meeting of the top with said sides. Each of these plates 9 is provided with a series of apertures 10 which extend along those edges of the plate which are connected to the side of the tank 3.

A top 11 is provided for the tank 3 and this top may be bound in place by an edging of angle iron 12. The top 11 is provided with a central opening or aperture 13 which is closed by a door 14 which is secured to the top by hinges 15, or otherwise.

A shaft 16, provided with a crank arm 17 depends through a central aperture in the door 14 and to this shaft is rigidly affixed a paddle or dasher 18. While the shaft 16 is described and shown as having a crank arm for operative purposes, it is to be understood that any form of gearing which is suitable for the purpose may be used.

The dasher is secured to the shaft 16 in any usual and well known manner, such as that herein shown wherein straps 19 embrace the shaft and have their out-turned ends secured to the dasher. The edges at opposed ends of the dasher are serrated to form teeth or projections 20. Extended along the edge of each end and overlying

the points of the teeth 20 is a strap 21, the ends of which are bent, as shown to engage the upper and lower edges of the dasher for a short distance, to which edges the strap ends are secured in any preferred manner.

In practice the invention is operated in the following manner:

Clothing is placed in the tank 3, together with a suitable washing fluid, such as soapy water, and the cover or lid closed. The dasher 18 is then caused to revolve. Because of the open spaces formed between the teeth and the bar or strap 21 which covers the points of the teeth, when the dasher ends 15 strike the clothing the water expressed from said clothing will be free to run through these openings.

Likewise as the clothes are dashed or drawn over the surfaces of the plates 5 or 9 20 water is expelled and forced through the openings in these plates.

By this means a continuous circulation of water through the clothing is set up and has a tendency to thoroughly and easily clean 25 the clothes.

Having thus described the invention, what is claimed as new and sought by Letters Patent, is:

1. A clothes washer, including a rectangular tank, plates overlying a portion of the

angles formed between two opposed sides of the tank and the top to form compartments, plates overlying the angles formed by the other two opposed sides of the tank and the bottom to form compartments, said plates 35 provided with apertures to permit circulation through said compartments, and an agitator within the tank.

2. A clothes washer, including a rectangular tank, plates overlying portions of the 40 angles formed by the meeting of two opposed sides of the tank with the top of the tank to form compartments, each plate bent to form a ridge, plates overlying the angles formed by the meeting of the other two opposed sides of the tank with the bottom, said plates likewise forming compartments and bent to provide ridges, said plates 45 provided with apertures to permit circulation through the compartments, and an agitator 50 within the tank.

In testimony that I claim the foregoing as my own, I have hereto affixed my signature in the presence of two witnesses.

BERT NELSON.
